BOOKBINDING

Joseph Edward Pitts, Oakland, Calif.

Application November 8, 1933, Serial No. 697,126

6 Claims. (Cl. 281—21)

My present invention relates to bookbinding, and more particularly to a new and improved method of stitching and securing the leaves of a book together which will provide a binding of great flexibility.

An object of my invention is to provide an improved method of stitching the leaves of a book together in an effective manner to produce a strong, durable and flexible binding.

Another object of my invention is to provide means in a stitched binding for a book which will relieve the tension upon the individual threads of the stitching when the book is opened and produce a flexible binding.

Other objects and advantages of my invention will be in part pointed out and in part evident to those skilled in the art from the following description thereof.

In a prior art Patent Number 1,585,076, issued May 18, 1926, to Carl F. Brenne, there is disclosed a method of bookbinding wherein the book is divided into a number of stitched sections having sewed to each side thereof a gummed fabric, by means of which the several sections can be secured together. In this disclosure the sections of the book are stitched together tightly with a straight stitching and then secured in book form by the gummed fabric. This form of binding has met with considerable success in binding work.

However, the provision of gummed fabric upon each side of the sections of the book, as disclosed in this patent, tends to stiffen the binding so that when the book is opened to an extreme position the fabric either pulls apart and/or the threads of the stitching pull therethrough. Therefore, it is a further object of my invention to provide a method of binding which is an improvement over the above disclosure and that is well adapted to the binding of ledgers, bank check books and the like, wherein a binding of great flexibility is required in order to permit a flat opening of books of this character for the convenient writing of entries therein.

In carrying out my invention, I divide the book into a number of sections and sew each section together, with a gummed fabric strip at one side and preferably an unguammed adhesive repelling and yielding fabric strip or cord at the other side, by staggered stitching. In this arrangement the yielding fabric strip may be gummed, provided said strip has a yielding thickness which will also render the adhesion of the gum more or less yielding. The objects of the invention can also be obtained without the gummed fabric

strips by securing the sections together by other means.

While the method of binding contemplated by my invention is adapted to the binding of edition work and the rebinding of all types of books, it will be found particularly useful in binding account books and the like which, for convenience, must be capable of lying flat when opened. One field in which I have successfully used my method is in the binding of bank check books and, therefore, I shall describe my invention in connection with such books.

In the drawing wherein I have shown, by way of illustration and not of limitation, preferred embodiments of my invention;

Figure 1 is a perspective view of a bank check book with a corner broken away to disclose one arrangement contemplated by my invention.

Figure 2 is a perspective view of the bank check book shown in Figure 1 with the pages opened.

Figure 3 is an enlarged fragmentary sectional view showing several sections of the book as pulled apart to more clearly illustrate the arrangement thereof, and

Figure 4 is a view similar to Figure 3 showing the use of a yielding cord for relieving the tension and reinforcing the stitching when the book is opened.

In the drawing 10 designates the individual leaves of a book and the numerals 11 and 12 designate respectively the front and back covers of the book. The covers 11 and 12 are secured over the leaves of the book by a back 13 of fabric, leather or other flexible material. In assembling the book the leaves 10 are arranged in groups or sections and the leaves of each section are sewed together by a staggered stitching with a thread

14. The expression staggered stitching, as used herein, is to be understood to mean a stitching wherein the threads pass through needle holes arranged in two rows along the line of the stitching and jump diagonally from one row of holes to the other as the stitching proceeds. This form of stitching is preferred as it crosses the longitudinal fibers or threads of the elements, which are to be described hereinafter as combined in the stitching, and places the tension, resulting from an opening of the book, upon the alternate stitches. This form of stitching also provides a greater length of thread than a straight stitching and thereby lends further flexibility to the binding.

After the leaves 10 of the book are collected in sections, I sew them together with a gummed fabric tape 15 on one side and a gummed or un-

gummed yielding fabric tape 16 on the other side. The fabric tape 15 is disposed with its gummed surface away from the section of leaves to which it is sewed, and if a gummed yielding fabric tape 16 is used its gummed surface will also be disposed away from the leaves of the section. I prefer to use an ungummed and adhesive repelling yielding fabric tape 16, as such a tape, owing to the absence of the gum or glue, has greater yielding characteristics. Instead of the yielding fabric tape 16, I may also use a single cord 17, over which the loops of the thread 14 pass. This latter arrangement provides an extremely flexible binding when a heavy cotton or silk crochet yarn 15 is used for the cord 17.

When the several sections of the book leaves 10 are assembled together, in accordance with the above outlined procedure, they can be secured in book form by moistening the gum on the fabric tape 15 and pressing the sections together until the gum has dried. The covers 11 and 12 can then be applied to the assembled sections in any suitable manner.

The sewing of the book leaves into several sections, as described above, limits the tension placed upon the stitching, by an opening of the book, to the stitching of the section in which the opening occurs and because of the shortness of the stitches, where they pass through the section, the fabric tape 16 or the cord 17 can yield sufficiently to relieve any strain upon the leaves 10 and the stitching. The fact that the stitching of each section of the finished book is independent of the stitching in the adjacent sections, and is limited to a small number of leaves, permits the book to be opened flat, even to an extent which will bring the stitching into view, as shown in Figure 2 of the drawing. When the book is opened flat, as shown in the drawing, the flexible gummed fabric tapes 15 between the sections will permit the individual sections of the book to adjust themselves, with respect to each other, and the strain upon the stitching will exist only in the particular section of the book which is opened. Because of the relatively small number of leaves in each section, the particular form of stitching and the yielding fabric tape 16 or the single yielding cord 17 will afford sufficient give in the threads of the stitching to prevent a tearing of the leaves 10 when the book is opened flat in any section. In practice, I have found that the most satisfactory results are obtained when the leaves 10 are sewed into sections that are not more than three-sixteenths of an inch ($\frac{3}{16}$ ") in thickness.

The most convenient method of applying the gummed fabric tape 15 and the yielding fabric tape 16 or the yielding cord 17 to the leaves of each section is to feed these tapes, or the tape 15 and the cord 17, from suitable rolls or spools disposed adjacent the sewing machine head. These tapes, or a tape and a cord, can then be fed along with the stitching as the sections are moved one behind the other under the needle of the sewing machine. If a guide is provided for properly locating the edge of the leaves 10 of each section on the line of the stitching, the gummed fabric tape 15 can also be directed into position with the same guide. The yielding fabric tape 16 or the cord 17 can then be located in line with the stitching at the top of the section by forming a groove in the underside of the presser foot upon the head of the sewing machine. If this procedure is followed a number of sections can be sewed in a continuous succession, after which the tapes 15 and 16, or the tape 15 and

the cord 17, can be cut to permit a stacking of the sections.

Upon referring to Figure 3 of the drawing, it will be seen that the yielding tape 16 is about one half as wide as the gummed fabric tape 15. The difference in the widths of these tapes permits the gummed fabric tape 15 to overlie the flexible fabric tape 16 and contact the top leaf of the underlying section to thereby secure the two sections together. At this point it will appear that the gummed fabric tape 15 will firmly adhere to the yielding tape 16. This will not be true, however, if the yielding tape 16 is of loose weave and sufficiently thick or nappy to provide the necessary yielding feature described above. When the cord 17 is used, instead of the tape 16, the amount of adhesion between it and the gummed tape 15 will be negligible. The preferred arrangement is to prevent an adhesion between the gummed fabric tape 15 and the yielding tape 16 or the yielding cord 17. This may be accomplished by forming the latter tape and/or the cord 17 of adhesive repelling material such as silk, rayon or of a mercerized fabric, as these fabrics will not adhere firmly to the gummed surface of the fabric tape 15.

Upon referring to Figure 4 of the drawing, it will be seen that the cord 17 is disposed between the rows of holes formed in the leaves of the section by the sewing needle and that the threads cross back and forth over the top thereof. Under these conditions, the cord 17, in addition to forming a yielding surface for the stitches, also serves to reinforce the top leaf of each section in no less an effective manner than does the yielding tape 16.

While I have, for the sake of clearness and in order to disclose the invention so that it can be readily understood, described and illustrated specific devices and arrangements, I desire to have it understood that this invention is not limited to the specific means disclosed, but may be embodied in other ways that will suggest themselves to persons skilled in the art. It is believed that this invention is new and it is desired to claim it so that all changes as come within the scope of the appended claims are to be considered as part of this invention.

Having thus described my invention, what I claim and desire to secure by Letters Patent is—

1. An improved bookbinding comprising in combination a plurality of sections of leaves having a narrow ungummed tension relieving fabric tape on one side and a wide gummed fabric tape on the other side, all of which are sewed together with a staggered stitching, said plurality of sections being superimposed upon each other and adhesively secured together by the gummed fabric tape at a point removed inwardly from the stitching.

2. An improved bookbinding comprising in combination a plurality of sections of leaves having a narrow tension relieving silk tape on one side and a wide fabric tape with an exposed gummed surface on the other side, all of which are sewed together with a staggered stitching, said plurality of sections being superimposed upon each other and adhesively secured together by the free inner edge of the gummed fabric tape at a point removed inwardly from the stitching.

3. An improved bookbinding comprising in combination a plurality of book sections having a fabric tape with an exposed gummed surface sewed to one side thereof by a staggered stitching, whereby two or more of said sections may be adhesively secured together by said tapes when superimposed one upon another, and a stitch ten-

sion relieving tape at the other side of each of said sections and disposed beneath the stitching thereof.

4. In an improved binding for books and the like, the combination of a plurality of sections of leaves, a relatively wide fabric tape having an exposed gummed surface sewed to one side of each of said sections with a staggered stitching, and an adhesive repelling fabric at the other side 5 of each of said sections also secured thereto by said stitching, whereby a number of said sections may be superimposed upon each other and adhesively secured together independently of said stitching.
- 10 10 of each of said sections also secured thereto by said stitching, whereby a number of said sections may be superimposed upon each other and adhesively secured together by said gummed tape at a point removed inwardly from said stitching.
- 15 15 5. In an improved binding for books and the like, the combination of a plurality of sections of leaves, a relatively wide gummed fabric tape

sewed to one side of each of said sections with a staggered stitching, and a tension relieving and adhesive repelling tape at the other side of each of said sections also secured thereto by said stitching, whereby a number of sections may be 5 superimposed upon each other and adhesively secured together independently of said stitching.

6. In an improved binding for books and the like, the combination of a plurality of book sections each comprising a relatively small number 10 of leaves, said sections being independently stitched together, means for adhesively securing said stitched sections together to form a complete book, and means for preventing adhesion between the book sections along the line of the stitching 15 of each section.

JOSEPH EDWARD PITTS.
